(57) **CLAIM**

The ornamental design for a straight clip for holding a coaxial cable or electrical cord, as shown.

DESCRIPTION

FIG. 1 is a front and right side perspective view of a straight clip for holding a coaxial cable or electrical cord, showing my new design;

FIG. 2 is a right side view thereof;

FIG. 3 is a left side view thereof;

FIG. 4 is a bottom end view thereof;

FIG. 5 is a top end thereof;

FIG. 6 is a front view thereof; and,

FIG. 7 is a back view thereof.

The straight clip for holding a coaxial cable or electrical cord is shown with a symbolic break in its length. The appearance of any portion of the straight clip for holding a coaxial cable or electrical cord between the break lines form no part of the claimed design. The broken lines in the drawings depict the boundary of the claim and form no part of the claimed design.
